UNITED STATES PATENT OFFICE.

ARCHIE N. RUTAN, OF ELMIRA, NEW YORK.

VALVE.

No. 918,918.

Specification of Letters Patent.

Patented April 20, 1909.

Application filed December 14, 1908. Serial No. 467,382.

To all whom it may concern:

Be it known that I, ARCHIE N. RUTAN, a citizen of the United States, residing at Elmira, in the county of Chemung and State of New York, have invented certain new and useful Improvements in Valves, of which the following is a specification.

This invention relates more particularly to improvements in valves adapted to control the admission to and exhaust from the opposite ends of the cylinders in pneumatic presses, hoists, and other fluid operated appliances, wherein it is required to stop and hold a piston at any point of its travel in either direction; and to start it again upon its travel, either in the same direction in which it was going, or in the opposite direction. I do not confine myself to this use of my valve, however, as it may be employed in connection with any apparatus requiring three-way control.

The object of my invention is to provide a simple and effective valve of this character, which will be positive in action to close off both admission and exhaust, and whereby leakage past the valve, either from the exhaust or admission sides of the cylinder, will be effectually prevented.

I attain my object by constructing the valve in the manner illustrated in the accompanying drawings, in which—

Figure 1 represents a side elevation of the valve, with the controlling lever in mid position; Fig. 2, a plan view thereof; Fig. 3, a sectional view on the line $x-x$ in Figs. 2, 4, and 5; Fig. 4, a plan view of the valve with the cap and operating lever removed; and Fig. 5, a similar view of the valve casing with the valve removed.

Like numerals designate like parts in the several views.

In carrying out my invention I provide a cylindrical valve casing 1, closed at its open end with a cap 2. A cylindrical valve 3 is fitted into a corresponding chamber in the valve casing, and is free to rotate therein. At diametrically opposite sides, this valve is provided with two Y-shaped passages, comprising a trunk portion 4, and the two branches 5 and 6, respectively. The closed end of the valve casing is provided with an opening adapted to receive the pipe 7, which leads from the source of fluid pressure supply. This opening is preferably at the center, and from it lead two passages 8, 8, to ports positioned on the line of travel of the

trunks 4 of the Y passages in the valve; so that one or the other of said passages will be placed in register with one of said ports when the valve is turned to the right or left. The 60 valve casing is also provided at 9, 9, with two exhaust passages, so positioned as to be also in the line of travel of the Y passages of the valve; so that when one of said passages is in communication with one of the admission 65 ports 8, the other passage will be in communication with an exhaust port 9. In the cap I provide two diametrically opposite openings 10, into which are screwed the pipes which lead to the opposite ends of a cylinder 70 to control the motions of a piston contained therein; or these pipes may lead to any appliance wherein the flow of fluid is to be controlled in a like manner. The ports 10 and the valve openings into the branches 5 and 6 75 of the valve Y's are located in the same circular line of travel; so that, when the branch 6 of the Y passage at one side of the valve is in register with the port 10 on that side, the opening into branch 6 of the opposite Y will 80 be in register with the opposite port 10.

The valve 3 is provided with a stem 13, which passes through the cap 2, and has attached to it an operating lever 14. This lever is provided with a locking latch 15, 85 adapted to engage notches in a segment 16 on the cap 2. The latch 15 is held in engagement with the segment notches by means of a spring 18, and is thrown out of engagement therewith, when the valve is to be turned, by 90 pressing upon the pin 17.

In the position in which the valve is shown in the several views, admission and exhaust is cut off from the pipes 11 and 12; and it will be noted that the passages through the 95 valve are positioned with their trunks midway between the admission and exhaust ports 8 and 9, thus forming a double shut-off between the ports 10 and the admission and exhaust ports 8 and 9. If, now, it is desired 100 to admit the fluid to pipe 12 and to exhaust from pipe 11, the operating lever will be turned to the right, thereby placing the trunk of the Y passage on the left hand side in communication with the admission port 8 on said side, the fluid passing through branch 5 to port 10, leading to pipe 12. At the same time the trunk of the Y passages on the right hand side will be placed in register with the exhaust port 9 on said side, and branch 5 will 105 register with the right hand port 10. By throwing the operating lever over to the left,

the Y passages will be reversed so as to place pipe 12 in communication with the exhaust passage 9 on the left hand side, and the pipe 11 in communication with the admission port 8 on the right hand side. By setting the valve in intermediate positions the admission and exhaust will be correspondingly adjusted and controlled. The valve seats against the closed end of the casing and also against the cap, thereby rendering it impossible for the admission and exhaust to pass by leakage from one side of the valve to the other.

What I claim as my invention and desire to secure by Letters Patent is—

1. A cylindrical valve having two longitudinal Y-shaped passages, in combination with a chamber in which the valve is revolvably mounted, said chamber being provided at one end with admission and exhaust ports adapted to be placed alternately in communication with the trunks of the respective Y passages, and at the other end with two ports each adapted to be placed in communication alternately with the branches of the respective Y passages.

2. A cylindrical valve having two longitudinal Y-shaped passages, in combination with a chamber in which the valve is revolvably mounted, said chamber being provided at one end with admission and exhaust ports adapted to be placed alternately in communication with the trunks of the respective Y passages, and at the other end with two ports each adapted to be placed in communication alternately with the branches of the respective Y passages, and said ports and passages being so positioned relatively to one another, that, when the valve is in closed position, the trunk of each Y passage will lie

between an admission and exhaust port and be cut off from both, and the branches of said passages will lie at opposite sides of a port at the other end of the chamber and be cut off therefrom.

3. The combination of a valve casing provided with a cylindrical chamber having at one end two sets of oppositely disposed admission and exhaust ports, the admission ports being connected to a common source of fluid supply and the four ports being set in a circle around the center of the chamber, a cylindrical valve fitted to turn in the chamber and provided with two oppositely disposed longitudinal Y-shaped passages, the trunk portions of said passages being positioned in the same circle with the admission and exhaust ports aforesaid and each adapted to lie between an admission and an exhaust port when the valve is in closed position, a cap to close the chamber, said cap forming a seat for the outward end of the valve and being provided with two oppositely disposed ports and passages, said ports being each positioned between the branches of a Y passage through the valve, when the valve is in closed position, whereby said cap ports may be placed alternately in communication the one with the admission and the other with the exhaust as the valve is turned in one direction or the other, and the valve stem passing through the cap and provided with an operating lever.

In testimony whereof I have affixed my signature, in presence of two witnesses.

ARCHIE N. RUTAN.
